Specification for Design.

Patented Oct. 4, 1921.

Application filed May 16, 1921. Serial No. 470,016. Term of patent 14 years.

To all whom it may concern:

Be it known that I, HARRY DALITZ, a citizen of the United States, residing at Cleveland, in the county of Cuyahoga and State of Ohio, have invented a new, original, and ornamental Design for a Steamer, of which the following is a specification, reference being had to the accompanying drawing, forming part thereof, in which—

Figure 1 is a plan view, Fig. 2 a side elevation, and Fig. 3 a bottom view of a steamer, showing my new design.

I claim:

The ornamental design for a steamer, as shown.

HARRY DALITZ.
